POURING DEVICE

Samuel Clare, Maplewood, N. J., assignor to
 Claremould Plastics Company, Newark, N. J.,
 a corporation

Application July 27, 1948, Serial No. 40,900

2 Claims. (Cl. 215—79)

1

This invention relates to pourers.

Broadly, it is an object of the invention to provide a pourer particularly adapted for liquor bottles in order to permit the pourer to easily dispense a desired amount of liquor in a glass providing a more uniform flow of liquor in not too large a stream so that the pourer can more readily control the amount desired to be poured.

A further object of the invention is to provide a bottle stopper of a flexible plastic which will safely seal the neck of a bottle and at the same time will not rot or deteriorate with age as will a cork.

A further object of the invention is to provide a square, hexagonal, octagonal or other form having angles in the nature of a channel depending from the base of the pourer to prevent the bottle stopper portion from revolving and to maintain the same relationship to the pourer so that the air holes in the bottle stopper portion and the pourer will be properly aligned.

A further object of the invention is to provide a pourer which can be inexpensively and rapidly formed at the same time making a durable and long lasting device superior to well known bottle stoppers now on the market formed of cork in association with pourers of other materials, such as plastic, metal and like materials.

For a fuller understanding of the nature and objects of this invention, reference is had to the following detailed description in connection with the accompanying drawing, in which:

Fig. 1 is a side view of the device.

Fig. 2 is a view taken through line 2—2 of Fig. 3.

Fig. 3 is a rear view.

Fig. 4 is a view taken through line 4—4 of Fig. 2, and

Fig. 5 is an isometric projection view of the bottle stopper portion.

Referring to the drawings, numeral 10 represents a pourer comprising an upper portion 11, preferably made of a plastic material and a bottle stopper portion 12, preferably made of a flexible plastic such as polyethylene, which is seated in the base 13 of the upper portion 11 as will be hereinafter described.

The upper portion 11 is comprised of the base 13 which has a flange 14 and a channel 15 between the bottom wall 16 and the flange 14. The upper portion also has a neck 17 and a substantially flat hollow upper structure 18 and a spout 19 leading into the upper structure 18, as will be further described. The upper structure 18 has a pouring chamber 20 and an air chamber 21. Both chambers are divided by a wall 22, the

bottom portion of which is vertical and the upper portion diagonal. A small opening 23 in the wall 22 permits air to communicate between the pouring chamber 20 and the air chamber 21. An opening 24 is also provided in the back wall of the upper structure 18 which provides atmospheric pressure for the air chamber 21. The spout 19 communicates with the pouring chamber 20. A hingeable lid or cover 25 is provided in the upper portion of the spout which pivots upon a fin 26 so that when the pourer is in upright position, as shown in Figs. 1, 2 and 3, the cover 25 closes the spout 19. However, when the pourer is tilted toward the horizontal position, the cover 25 automatically pivots to a vertical position, so that it does not cover the spout 19 and permits the liquor to flow through the spout 19.

The upper portion 11 is made of two cooperating halves split longitudinally. Tits 27 and 28 are provided to cooperate with small holes on the opposite edge in order to properly align the two halves when they are sealed together with an adhesive.

The bottle stopper portion 12 is preferably made of a flexible plastic, such as polyethylene, and comprises a round, slightly tapered lower portion 29 to permit it to be seated and wedged into the neck of a bottle, the flexibility of the material providing a firm and resilient grasp, so that when the bottle is tilted for pouring, the pourer will not become dislodged from the bottle and only manual force will seat it and remove it from the neck of the bottle. The upper portion 30 of the bottle stopper 12 can be made substantially square, as shown in Fig. 5, or the upper portion 31 can be made octagonal, as shown in Fig. 4. In fact, any polygon can be used in order to prevent rotation of the bottle stopper portion 12 with relation to the upper portion 11. Of course the channel 15 is made in the form of a square or octagon or other shape to conform to the shape of the upper portion of the bottle stopper. The bottle stopper 12 comprises a large pouring opening 32 and a smaller opening or air channel 33, as shown in Figs. 2 and 5. In like manner the bottle stopper portion shown in Fig. 5 has a pouring opening 32' and an air channel 33'. The air opening 33 is aligned with an opening 34 in the bottom wall 16 and the pouring opening 32 is aligned with a larger opening 35 in the bottom wall 16. In like manner, if the bottle stopper portion shown in Fig. 4 is used in place of the one shown in Fig. 5, pouring opening 32' is aligned with opening 35 while air channel 33' is aligned

with opening 34. In Fig. 5 opening 32 and the channel 33 are divided by a vertical wall 36, while the opening 32' and the channel 33' of the bottle stopper shown in Fig. 4 is divided by a vertical wall 36'.

In operation, with the pourer in the neck of a bottle of liquor, as the bottle is tilted to a horizontal position, the liquor passes from the bottle through the pouring opening 32 of the bottle stopper 12, through the opening 35 and flows into the pouring chamber 26 and thence through the spout 19. Atmospheric pressure is provided through the openings 24 and the air chamber 21 through the openings 34 and through the air channel 33 so that the flow of liquor will not be prevented due to differences in pressure between the outside atmosphere and the pressure within the bottle.

While the pourer has been primarily designed for the pouring of liquor, it is obvious that the pourer can be used for other products, such as olive oil, syrups, flavors, Worcestershire sauce, salad dressings, and like liquids. It is also within the realm of this invention to permit the pouring of fine granular substances, such as sugar, salt and other products of like fungible nature.

It is further obvious that various changes and modifications may be made in the details of construction and the arrangements of parts without departing from the general spirit of the invention.

I claim:

1. A pourer comprising an upper portion and a lower bottle stopper portion; said upper portion having a base, a pouring chamber, an air chamber, a pouring spout communicating with said pouring chamber and a bottom wall for said upper portion; an air hole in said air chamber leading to the outside atmosphere, an opening between said air chamber and said pouring chamber, a large opening in said bottom wall, communicating with said pouring chamber, a smaller opening in said bottom wall communicating with said air chamber, a portion depending from said bottom wall, said depending portion comprising a flange and a channel between said flange and said bottom wall, said bottle stopper portion comprising a lower portion and

an upper polygon portion, said upper polygon portion firmly seated within said channel, a pouring opening in said bottle stopper portion communicating with said large opening in said bottom wall and said pouring chamber and an air channel in said bottle stopper portion communicating with said smaller opening in said bottom wall and said air chamber.

2. A pourer comprising an upper portion and a lower bottle stopper portion, said upper portion having a base, a pouring chamber, an air chamber, a pouring spout communicating with said pouring chamber, a lid for said pouring spout, a bottom wall for said upper portion, an air hole in said air chamber leading to the outside atmosphere, an opening between said air chamber and said pouring chamber, a large opening in said bottom wall communicating with said pouring chamber, a smaller opening in said bottom wall communicating with said air chamber, a portion depending from said bottom wall, said depending portion comprising a flange and a channel between said flange and said bottom wall, said bottle stopper portion comprising a lower tapering circular portion of resilient plastic material and a substantially square upper portion, said substantially square upper portion firmly seated within said channel, a pouring opening in said bottle stopper portion communicating with said large opening in said bottom wall and said pouring chamber and an air channel in said bottle stopper portion communicating with said smaller opening in said bottom wall and said air chamber.
